AQUARIUM SIPHON

Richard C. J. Palson, Medfield, Mass., assignor to Bio-zonics Corp., Natick, and Fred A. Ravreby, Framingham, Mass., fractional part interest to each

Filed July 29, 1970, Ser. No. 24,208

Term of patent 14 years

Int. Cl. D30—01

U.S. Cl. D30—12

FIG. 1 is a front elevation of an aquarium siphon embodying my new design, the rear being a mirror image of the front shown;

FIG. 2 is a left end elevational thereof, the right end being the same as the left shown;

FIG. 3 is a top plan view thereof;

FIG. 4 is a bottom plan view thereof;

FIG. 5 is a cross-sectional view taken on line 5—5 of FIG. 1; and

FIG. 6 is a front elevation of a modified form of the aquarium siphon shown in FIG. 1.

I claim:

The ornamental design for an aquarium siphon, as shown and described.
